DESIGN FOR A HAT

Oscar Friedman, New York, N. Y.

Application August 31, 1934, Serial No. 53,135

Term of patent 3½ years

To all whom it may concern:

Be it known that I, OSCAR FRIEDMAN, a citizen of the United States of America, residing in Manhattan, county of New York and State of New York, have invented the new, original, and ornamental Design for a Hat, of which the following is a specification, reference being had to the accompanying drawing, forming part hereof, wherein,

The characteristic feature of my design resides in the arrangement of the tapered strips of felt stitched radially on the crown of the hat.

I claim:

The ornamental design for a hat, substantially as shown and described.

OSCAR FRIEDMAN.
